UNITED STATES PATENT OFFICE.

DAVID McINTYRE, OF DETROIT, MICHIGAN, ASSIGNOR OF ONE-HALF TO GEORGE D. BALL, OF DETROIT, MICHIGAN.

BUILDING-BLOCK.

952,080.

Specification of Letters Patent. Patented Mar. 15, 1910.

Application filed March 26, 1908. Serial No. 423,390.

To all whom it may concern:

Be it known that I, DAVID McINTYRE, a citizen of the United States, residing at Detroit, in the county of Wayne, State of Michigan, have invented certain new and useful Improvements in Building-Blocks; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to new and useful improvements in building blocks, more particularly designed for the building of walls and the erection of chimneys, and consists in the construction and arrangement of parts 20 hereinafter more fully set forth and pointed out particularly in the claims.

The object of the invention is to produce a building block of the character described, wherein the arrangement is such as to enable 25 a wall or chimney to be quickly and perfectly built, and wherein provision is made after a portion of a wall or chimney has been built, whereby the whole may be bound together vertically and transversely 30 by pouring cement or mortar into the vertical passages formed through said blocks which communicate with horizontal channels in the faces thereof, making a wall so formed, of unusual stability.

35 The above object is attained by the formation of the blocks and their association in a wall as illustrated in the accompanying drawings, in which:—

Figure 1 is a plan view of a portion of a 40 wall built of blocks formed in accordance with my invention. Fig. 2 is a perspective view looking at the upper face of one of said blocks. Fig. 3 is a perspective view showing the under face of one of said blocks. Fig. 4 is an enlarged transverse section through a 45 building block made in accordance with my invention. Fig. 5 is a plan view of a corner block. Fig. 6 is a portion of a wall, partly in section, built of blocks made in accordance 50 with my invention, the sectioned portion of the wall showing the cement binder filling the registering vertical apertures and longitudinal channels in the faces of the block for a certain distance, the remaining portion of said sectioned parts showing said

apertures and channels free from said cement. Fig. 7 is a transverse section through a wall built of my improved blocks, as on line 7—7 of Fig. 1, the binder of mortar or cement being omitted. Fig. 8 is a plan view 60 of a chimney block. Fig. 9 is a sectional view through said block, as on line 9—9 of Fig. 8.

Referring to the characters of reference, 1 designates the block employed for constructing a wall, which is oblong and of rectangular shape, and provided with a projecting L 2. Each block is provided in its upper face with a longitudinal channel 3. Between said channel and the outer face of the block is a flat marginal portion 4, shown more clearly in Fig. 4. Projecting vertically from the face of the block and extending longitudinally thereof between the inner margin of the channel 3 and the inner face 70 of the block, is a V-shaped rib 5. On each side of said rib at the base thereof are the flat marginal bearing surfaces 6, the horizontal plane of which is above the plane of the marginal surface 4, as will be seen on 80 referring to Fig. 4, the purpose of which will be hereinafter explained. Crossing the channel 3 at intervals are the partitions 7 which afford bearing supports for the succeeding block placed thereon and whose upper edges are on a plane with the marginal surfaces 6. Passing vertically through the body portion of the block are the oblong apertures 8 which lead from the bottom of the channel 3 and are disposed on opposite 85 sides of the partitions 7. The L portion 2 of the block also has a groove 9 in its upper face, and leading from the bottom of said groove and passing through said portion of the block is an oblong aperture 10. In the 90 ends of the body portion of the main blocks are formed vertical channels 11 which when the blocks are placed end to end, form vertical passages between the ends of the blocks, as clearly shown in Fig. 1. The under face 100 of each block is flat, excepting along its inner margin where it is provided with a V-shaped channel 12 adapted to receive the rib 5 of the block below. By this arrangement when the blocks are laid up in a wall, they 105 are perfectly centered and positioned, obviating the time and care usually required in laying up a wall of blocks without these interlocking and positioning members.

The L-shaped block herein shown is de- 110

signed to be employed in laying up a double or hollow wall, as shown in Fig. 1, with an air space 13 between the outer and inner sides of the wall. The blocks are so laid 5 that the L portions thereof extend inwardly from opposite sides in succession and lie on each other so as to tie the sides of the wall together with the body portions of the blocks breaking joints, as shown in Fig. 6. The 10 blocks are of such shape and the apertures 8 and 10 formed therethrough are so positioned as to cause said apertures in the blocks which are laid up in the wall, to register with like apertures in the blocks 15 below, so that after the wall has been laid for a certain distance, cement or mortar of the proper consistency, may be poured into said apertures, as shown at 20 in Fig. 6, to fill them, the cement being sufficiently fluid 20 to flow horizontally along the channels 8 in the blocks so as to fill said channels as well as the vertical apertures, whereby the blocks in the wall are tied together by a continuous binder of cement or mortar extending up- 25 wardly through the vertical apertures there- in which are entirely filled thereby, as well as through the longitudinal channels along which the cement flows to effect a perfect distribution thereof into all of the vertical 30 apertures through the blocks. Mention has been previously made of the fact that the outer marginal surfaces 4 of the blocks are lower than the plane of the inner surfaces 6, the purpose of which is to form a slight 35 opening between the faces of the blocks along their outer margin, as shown by dotted lines in Fig. 4, which opening communicates with the channel 3 and into which the cement or mortar will flow when the vertical 40 apertures and longitudinal channel are filled by the cement or mortar, thereby showing a mortar line between the blocks when they are laid up in a wall.

It will be noted that the block shown in 45 Fig. 5 is not provided with a vertical groove 11 in the body thereof at the end where the L is connected, but that said vertical groove is formed in the end of the L instead. This arrangement is necessary in a corner block 50 to enable the corner to be properly turned without exposing the channel or groove 11 in the outer face of the wall, and to enable a proper connection to be made with the blocks in the wall extending from said cor- 55 ner blocks.

The square blocks 14 shown in Figs. 8 and 9 which are designed for the construction of a chimney are, like the blocks 1, pro- 60 vided on their upper faces with a V-shaped 65 marginal rib 5 around the central opening 15 therethrough and on their under faces with a beveled marginal portion 16 adapted to receive the incline of one side of said rib when the blocks are placed together to prop- 70 erly position said blocks. The upper faces

of said blocks 14 are also provided with the groove or channel 17 having the marginal bearing surfaces 18 on each side thereof. Extending from the bottom of the channel 17 vertically through the blocks are the 70 apertures 19 which are caused to register when the blocks are laid up and through which cement or mortar is poured to bind the blocks together, the mortar flowing around the channel 17 from the vertical 75 apertures 19, filling said channel and bind- 80 ing the blocks firmly together not only be- 85 tween their horizontal faces, but by means of the vertical columns of cement or mortar which extend through and fill the aper- 90 tures 19 thereof in a manner similar to that illustrated in Fig. 6.

Having thus fully set forth my invention, what I claim as new and desire to secure by Letters Patent, is:—

1. A building block substantially rectangular in shape having a projecting tongue on one face near one margin, and in the opposite face a correspondingly disposed groove, the remaining portion of the face 90 of the block in which said groove is formed being flat, the face of the block carrying the tongue having a shallow concaved channel parallel with said tongue and near one margin of the block, said block having a plural- 95 ity of apertures formed through the body of the block leading from the base of said channel in one face and passing through the flat surface of the block on the opposite face.

2. A building block of substantially rec- 100 tangular shape having in one face a longi- 105 tudinal channel, there being a series of ap- 110 pertures leading from the base of said channel and passing vertically through the block, said block having marginal surfaces on each side of said channel, one of which surfaces is below the plane of the other.

3. An oblong block substantially rectan- 110 gular in cross section, having a longitudinal channel in one face thereof and a series of 115 vertical apertures extending therethrough leading from the base of said channel, said block having marginal surfaces on each side of said channel one of which is below the plane of the other, and transverse partitions 118 crossing said channel in the plane of the higher of said surfaces, the opposite faces of said block having engageable members adapted to co-act with like parts on similar blocks to position said block in a wall. 12

4. An oblong building block substantially rectangular in cross section, having a lon- 120 gitudinal channel in one face thereof and vertical channels in its ends registering with said longitudinal channel, said block also 125 having marginal surfaces on each side of said channel, one of which is below the plane of the other and having a plurality of vertical apertures passing therethrough lead- 130 ing from the base of said longitudinal chan-

nel, and a plurality of partitions crossing said longitudinal channel in the plane of the higher bearing surface of the block.

5. A wall composed of blocks having a plurality of vertical channels therethrough adapted to register when the blocks are laid in the wall, each block having in one face a horizontal channel communicating with and connecting said vertical channels and 10 with marginal surfaces on each side of said horizontal channel, one above the plane of the other, to form a slit between the marginal edges of the superimposed blocks communicating with said horizontal and vertical 15 channels, and a plastic binder filling the vertical and longitudinal channels of the blocks to bind them together in the wall.
6. An oblong L-shaped building block substantially rectangular in cross section, said 20 block having a plurality of vertical channels

therethrough and having a shallow concaved channel in its upper face connecting said vertical channels, the under side of said block being substantially flat, a plurality of shallow partitions crossing said concaved 25 channel, a V-shaped rib on one face of the block adjacent one margin thereon and parallel with said concaved channel, there being in the opposite face of said block a correspondingly disposed V-shaped groove, and 30 a channel in the end of the block near one margin communicating with the concaved channel in the upper face of the block.

In testimony whereof, I sign this specification in the presence of two witnesses.

DAVID McINTYRE.
